US0D1050264S

(12) **United States Design Patent** (10) Patent No.: **US D1,050,264 S**
(45) Date of Patent: ** Nov. 5, 2024

(54) **GAME CARD**

(71) Applicant: **DongGuan Tesmai Electronic Technology Co., LTD**, Guangdong (CN)

(72) Inventor: **Yinwei Liao**, Guangdong (CN)

(**) Term: **15 Years**

(21) Appl. No.: **29/954,264**

(22) Filed: **Jul. 25, 2024**

(30) **Foreign Application Priority Data**

Jun. 5, 2024 (CN) 202430343157.9

(51) LOC (14) Cl. **21-01**

(52) U.S. Cl.
